2,480,400

METHOD OF MAKING GRAVURE PRINTING PLATES

Arthur Dultgen, Manhasset, N. Y., assignor to
News Syndicate Co., Inc., New York, N. Y., a
corporation of New York

Application December 30, 1944, Serial No. 570,644

1 Claim. (Cl. 95—5.6)

1

This invention relates to a method of making a gravure printing plate.

The invention is directed particularly to preparing gravure printing plates from half-tone printing plates so as to take advantage of the availability of half-tone plates and the hand-made corrections, such as color corrections, which are customarily present in such plates.

In preparing half-tone photographs by photographing through half-tone screens, the dot formation formed on the photographic plate is dependent upon the screen distance, time of exposure and the shape of the stop, so that numerous different half-tone dot formations are available. In preparing half-tone printing plates for relief printing, it is usual to obtain the greatest possible tone range by a half-tone dot formation which runs from a white ground containing minute black dots in the lightest tones to a black ground containing minute white dots in the darkest tones. For making a gravure plate, it is customary to reduce the tone range to about one-half the maximum tone range, so that, while the lightest areas are represented as before, the darkest areas are represented by a white field with large black dots just out of contact with one another or, in other words, in the same way that the middle tones are represented in a half-tone of maximum tone range. Prints of such half-tones of reduced range make resists which may be used in gravure etching because they produce a plate in which even the darkest tones are represented by separate cavities well adapted to hold the ink. Gravure plates made from such reduced range half-tones of course produce prints of reduced tone range and are, therefore, unsatisfactory unless the tone range of the print is increased by some means for causing a variation in the depth of the cavities. Such means are described in my Patent 2,096,794, issued October 26, 1937.

My present invention is directed to making a gravure plate from a full-range half-tone such as a half-tone photograph made for relief printing or a print from a half-tone plate. I have found that it is possible to break up the solid black areas and the black areas containing isolated white dots which occur in a full-range half-tone, without modifying the portions of the picture which appear as black dots of various sizes on a white background.

In accordance with my invention, this is accomplished by two successive exposures of the resist through which the plate is to be etched. The first exposure is made through a full-range posi-

2

tive half-tone transparency of the subject, while the second exposure is made through a positive transparency having a uniform dot formation consisting of slightly separated opaque dots on a transparent ground. It is important that the transparency with the uniform dot formation have the same screen size as the half-tone positive. In making the second exposure of the resist, the transparency with the uniform dot formation is turned so that the rows of dots lie in the same direction as the dots in the half-tone positive. The result of the second exposure is to break up the unexposed portions left on the resist by the first exposure into large isolated dots, without changing the size of the unexposed dots which have been left in the lighter tones after the first exposure. In order to produce a print having a full tone range, it is necessary to treat the resist so that it will produce cavities in the plate which vary in depth as well as in area.

In order to fully explain my invention, I will describe a specific method embodying it. In this description I shall refer to the accompanying drawings in which:

25 Fig. 1 is a flow diagram of an illustrative method embodying my invention; and

Fig. 2 is a diagram showing the combined effect of successive prints on a carbon tissue.

30 A full-range half-tone positive transparency of an original is prepared. It may consist merely of a contact print from a half-tone negative made by photographing the original through a half-tone screen for the purpose of producing a half-tone relief plate. More desirably, it is made from a mechanical print from a corrected half-tone plate. In this case, the positive transparency may be produced by making a mechanical print from the half-tone plate on a transparent material, or by photographing a mechanical print from the plate made on paper or other opaque material.

35 A positive transparency with a uniform half-tone dot formation having the same screen size as the half-tone positive is prepared. This is done by photographing a uniformly lighted field through a half-tone screen in a half-tone camera, making the exposure such as to produce disconnected dots. A contact print of the photograph may then be made, if necessary, in order to produce opaque dots on a transparent field. The dots are of uniform size and just out of contact with each other, such as those which occur at a middle tone of an ordinary half-tone positive. The screen size of this positive is the same

as the screen size of the full-range half-tone positive of the original.

The two positives are printed successively on an ordinary carbon tissue, that is to say, the carbon tissue is exposed successively through the full-range half-tone positive of the subject and through the positive with the uniform dot formation. It is important that in making two exposures the dot formations be in register.

The result of the two exposures of the carbon tissue is shown in Fig. 2. In this figure, the areas with vertical shading are those which are left unexposed when the tissue is exposed through the full-range half-tone positive of the original. For illustrative purposes, it is assumed that the half-tone positive shows merely a tone scale extending uniformly from the lightest tone at the top to the darkest tone at the bottom. The areas indicated by horizontal shading are those which are left unexposed when the tissue is exposed through the positive with the uniform dot formation.

The combined result of the two exposures is to expose all parts of the carbon tissue except those which were covered in both exposures and which are represented by cross-line shading in Fig. 2. It will be seen that in the darker tones shown in the lower part of the figure, the unexposed areas remaining after the two exposures consist of large disconnected dots, as distinguished from the solid unexposed area which remained after the exposure through the half-tone positive and before the second exposure was made. In the lighter tones, on the other hand, the unexposed areas remaining after the two exposures are the same as those remaining after the first exposure and before the second exposure. The second exposure in no way changes the unexposed dots left in the lighter tones after the first exposure, as each of them is fully covered by one of the larger opaque dots of the uniform dot formation positive, and this will be true even though there is a slight error in registration.

After the two exposures, the carbon tissue may be used as a resist in etching a gravure plate, and will result in producing a plate having disconnected cavities well adapted to hold the ink. Such a plate, however, does not give an accurate representation of the tones of the original. This is apparent from Fig. 2 where it is shown that after the two exposures, the unexposed areas (indicated by cross-line shading) which produce the cavities in the printing plate are of the same size in the darkest tones and in a tone near the middle tone, so that a print made from a plate engraved directly from the resist shown in Fig. 2 would lose those gradations in tone of the original which occur between the middle tone and the darkest tone. This difficulty is remedied according to my invention by printing a continuous-tone positive of the original on the carbon tissue after the full-range half-tone positive and the uniform dot formation positive have been printed on it.

The continuous-tone positive of the original may be merely a positive print of a continuous-tone photograph of the original or it may be a slightly blurred photograph of a mechanical print from a half-tone plate in which the dot formation of the print is lost. The effect of the exposure of the tissue through the continuous-

tone positive is to produce a graduated exposure of the previously unexposed areas of the tissue so that, on reversing and washing the tissue, the usual multiple-stage etching will produce deeper cavities in the darker areas than in the lighter areas.

My invention is most valuable when used to produce gravure plates from half-tone relief plates so as to obtain the advantage of hand retouching which has been done on such plates. This is particularly important in plates for the three-color or the four-color process. In order to obtain the benefit of such retouching, the full-range half-tone positive used in my method is produced from a mechanical print from the half-tone plate in either of the manners previously described. If this is done, it is not necessary that the continuous-tone positive be also obtained from a mechanical print from the half-tone plate, as the effect of the retouching is carried into the gravure plate to a sufficient extent if only the half-tone positive is obtained from the relief plate.

Various changes may be made in the specific method which has been described without departing from the scope of my invention. Thus, the order of the successive prints is not important. It is not necessary that the successive prints through the full-range half-tone positive and the uniform dot formation transparency be made directly on a carbon tissue or upon any type of resist. Any light-sensitive material may be exposed successively under the two transparencies and the combined print may thereafter be transferred to a resist. Where the invention is to be used in its best form to produce a plate with cavities differing in depth as well as in area, a carbon tissue should be used at least for the print from the continuous-tone positive.

40 What I claim is:

The method of making a gravure printing plate, which comprises successively printing in register on a carbon tissue a full-range half-tone positive of an original, a uniform half-tone dot formation of the same screen size consisting of disconnected opaque dots on a transparent field, and a continuous-tone positive of the original, and then producing a gravure plate by multiple-stage etching through said carbon tissue.
